TOW TARGET EXCHANGE DEVICE

Le Roy S. Jessen, Dayton, Ohio

Application October 23, 1946, Serial No. 705,114

1 Claim. (Cl. 273—105.3)

(Granted under the act of March 3, 1883, as
amended April 30, 1928; 370 O. G. 757)

1

The invention described herein may be manufactured and used by or for the Government for governmental purposes without payment to me of any royalty thereon.

This invention relates to a device for releasing and exchanging an aerial target carried on the end of an airborne tow cable.

It is customary to employ a release device at the trailing end of an aerial tow cable, whereby a target can be carried during gunnery practice, and said target, after having been subject to fire, can be released and dropped during flight, by means of a new exchange target applied at the leading end of the tow cable and then traveling along the cable onto said exchange device. When the gunnery practice is completed, a small sleeve on a lead line is launched on the tow cable, in the same manner as an exchange target, to release the last target used, and the cable with the small sleeve are then reeled into the airplane. Such release devices now used are rather crude in their construction and so are often slow and delayed in their operative movement in releasing the towed target.

It is an essential object of this invention to provide a compact and efficient tow target exchange device which will promptly and with certainty release the tow target when the traveler ring of the exchange target or of the final sleeve travels onto the device.

Another object of this invention is to provide such an exchange device which is simple and economical in construction, is compact in size, and is light in weight, as well as very effective in operation.

These and various other objects and advantages are attained with this invention as will become apparent from the following description, taken in connection with the accompanying drawings wherein the invention is shown in its preferred form, it being evident that other arrangements and forms of construction may be resorted to in carrying out the objects and purposes of this invention.

In the drawings:

Fig. 1 is partly a side elevational view and partly a vertical sectional view of this improved tow target exchange device, shown mounted on the end of a tow cable and in its target towing position.

Fig. 2 is partly a side elevational view including parts in vertical section and parts broken away, and shown in its target releasing and exchanging position.

Figs. 3 and 4 are cross-sectional views of this

device, taken respectively on lines 3—3 and 4—4 of Fig. 1.

In the drawings, this target exchange device is disclosed in a preferred form of construction which comprises an outer casing or body 11 being tubular and substantially cylindrical in form. This body 11 is connected to the trailing end of the tow cable 12, as by connecting means 13, the cable having its leading end suitably connected to the towing airplane, as is well understood in this art. Said connecting means is shown herein as including an outer conical casing 14 which is connected to said body 11 and contains therein a conical inner plug 15, having the rear end portion 16 of the cable 12 looped around said plug and clamped in place by means of the plug and casing and a head 17 pressed by a spring 18 against the cable end.

A latch or target holding and releasing lever 21 is pivotally mounted in said body 11, by a pivot pin 22, said latch being preferably in the shape of a flat bar and said pin extending through the intermediate part of the latch and through a pair of segmental blocks or bosses 23 which are interposed between the forward parts of the two sides of the latch bar and of the interior of said cylindrical body, said blocks being preferably secured in the housing, as by brazing or welding. This pin 22 has its ends seated in these blocks and in the cylindrical wall of the body, as best seen in Fig. 4.

As indicated in Fig. 1, when this improved device is in its normal towing position, the latch 21 extends longitudinally of the body 11 and is mainly housed therein. Said latch has a rounded upper shoulder 24 and also a tapering lower part or foot 25 at its leading end 21', and the latch has a depending hook 26 at its trailing end which normally projects through a slot 27 in the tubular body 11, in position to engage and hold a target lead ring or traveler ring 28 in place on the device with said ring having the target cable or target lead line 29 attached thereto and towing the target (not shown) as is well understood in this art. This latch bar 21 has a slot 30 provided in its trailing part to lighten it and facilitate the upward swinging of said part with the hook 26.

A trigger or latch operating and holding lever 31 is provided which is preferably channel shaped, being substantially yoke shaped in cross section and between the pair of spaced flanges or side arms 32 of this trigger is received the leading end 21' of the latch 21, so that the bight 50 which joins the side arms of the trigger is posi-

tioned adjacent said forward shoulder 24 on the latch. This trigger is pivoted at its lower end in the housing, by a pin 33 extending through said blocks 23 and through the housing wall.

The end 21' of the latch has a vertically extending slot or recess 34 in its lower part, thus allowing this end of the latch to move downward with this slot passing over said pivot pin 33 when said end swings downward for releasing the upwardly moving hook 26 from the target lead ring 28, as indicated in Fig. 2. The trigger 31 carries a cam pin or locking pin 35 with its ends seated in the spaced flanges 32, and a horizontal slot 36 extends from said vertical slot 34 longitudinally of the latch 21, so that this cam pin 35 can slide therein as the downwardly swinging trigger rides longitudinally upon the shoulder 24 of the latch and depresses the same.

It may be noted that when the device is in its normal target holding and towing position, the trigger 31 extends substantially vertically, as shown in full lines in Fig. 1, and the cam pin 35 then retains the latch in its horizontal target holding position. Furthermore, the center of the cam pin 35 is then situated forwardly or to the left of the center of pivot pin 33, so as to aid in holding the latch 21 secured or locked in its normal horizontal position. However, special means is additionally provided for constantly holding the trigger and therewith positively holding the latch in its upwardly extending position during the towing operation, and this means includes a plunger 37 slidably mounted in said horizontal slot 36 and also a spring 38 seated in a continuation or pocket 36' extending rearward from said slot thereby constantly urging said plunger to bear against said cam pin 35 for retaining the trigger in said extending position.

It should be noted that by this arrangement, in housing the plunger 37 with its actuating spring 38 within the latch 21, instead of outside thereof, space is saved and this device is made more compact and light.

When a towed target is to be released during flight, the new traveler ring 39 with the exchange target carried thereby is allowed to travel from the airplane rearwardly over the tow cable to this target exchange device which tows the fired target thereon, and when this new ring strikes and swings the trigger, the bight of the trigger promptly engages the shoulder 24 on the latch, as indicated in dotted lines in Fig. 1, and tilts down the latch end 21'; then, as indicated in Fig. 2, said ring in its rearward movement over the body 11 continues to depress the trigger and latch end 21' and thereby to raise the hook end of the latch until the hook 26 is withdrawn into the body 11, thus releasing and dropping the ring 28 with the attached fired tow target. While the exchange ring 39 thus passes beyond the trigger, in its rearward travel over the body toward its target-holding position, it serves to press

the protruding main part of the latch back into the body of the device. Furthermore, a leaf spring 41 is placed between the lower part of the latch and the housing, being secured at its rear end 42 to the latch, and it is flexed by the ring-releasing upward swinging of the latch, so that upon release of the trigger, said spring will return the latch to again extend the hook 26 into its holding position, for retaining this exchange ring 39 in place.

With this disclosed form of tow target exchange device a compact and light structure is provided whereby the release of the fired target can be effected promptly and with certainty.

15 I claim:

In a device for attachment to the trailing end of a towing cable for towing a target by its traveller ring and for substituting a replacement target for the trailing target, the improvement which comprises a hollow latch body capable of passing freely through a traveller ring and having means at the leading end for attachment to a towing cable, a latch of substantially the length and width of said body pivotally supported in said body intermediate the leading and the trailing ends, said body being provided with an axial slot to receive and contain said latch in the unactuated position, a hook carried on the trailing end of said latch diametrically opposite said slot, adapted, when said latch proper is in its normal unactuated position within said slot to protrude through an opening in said body thereby to arrest passage of a traveller ring over the trailing end of said body, a trigger at the leading end of said latch having one end hinged in said body and the free end extending radially beyond said body in the path of a traveller ring, a camming pin carried by said trigger offset in the unactuated position both radially and axially with respect to said hinge and passing through a slot extending lengthwise of said trigger, whereby swinging of the free end of said trigger toward the trailing end by the passing of a traveller ring thereover rocks said latch on said pivot to withdraw said hook into said body, axially extending spring and plunger means carried by said latch positioned to act against said camming pin to bias said trigger to the radially extended unactuated position, and a spring means urging said latch to the normal hook-projected position.

LE ROY S. JESSEN.
